Term of patent 14 years

(Cl. D26—14)

FIG. 1

FIG. 3

FIG. 2

FIG. 5

FIG. 4

Fig. 1 is a front perspective view of a portable tape recorder or similar article, showing my new design with the cover in open position;

Fig. 2 is a top perspective view with the cover in closed position;

Fig. 3 is a top plan view to a reduced scale;

Fig. 4 is a bottom plan view to a reduced scale;

Fig. 5 is a rear elevational view to a reduced scale; and

Fig. 6 is a side elevational view to a reduced scale, the opposite side being substantially a mirror image thereof.

The detachable carrying strap has been partly broken away in Figs. 2, 3 and 4 and has been omitted from Figs. 1, 5 and 6 for convenience in illustration.

I claim:

The ornamental design for a portable tape recorder or similar article, as shown and described.
